UNITED STATES PATENT OFFICE.

CALEB S. BRAGG, OF PALM BEACH, FLORIDA, AND VICTOR W. KLIESRATH, OF PORT WASHINGTON, NEW YORK, ASSIGNORS TO BRAGG-KLIESRATH CORPORATION, OF LONG ISLAND CITY, NEW YORK, A CORPORATION OF NEW YORK.

MEANS FOR OPERATING SUCTION-ACTUATED DEVICES IN CONNECTION WITH INTERNAL-COMBUSTION ENGINES.

Application filed June 25, 1925. Serial No. 39,420.

To all whom it may concern:

Be it known that we, CALEB S. BRAGG, a citizen of the United States, residing at Palm Beach, in the county of Palm Beach and State of Florida, and VICTOR W. KLIESRATH, a citizen of the United States, residing at Port Washington, in the county of Nassau and State of New York, have invented certain new and useful Improvements in Means for Operating Suction-Actuated Devices in Connection with Internal-Combustion Engines; and we do hereby declare the following to be a full, clear, and exact description of the invention, such as will enable others skilled in the art to which it appertains to make and use the same.

Our invention consists in the novel features hereinafter described, reference being had to the accompanying drawings, which illustrate one embodiment of the same, selected by us for purposes of illustration, and the said invention is fully disclosed in the following description and claims.

In the operation of vacuum brakes for automotive vehicles or other vacuum or suction actuated devices, in connection with internal combustion engines, it is extremely convenient to obtain the necessary suction or partial vacuum from a suction passage of the internal combustion engine, and located between the throttle valve for controlling the supply of explosive mixture, and the cylinder or cylinders of the engine. To this end it is convenient and desirable to connect the vacuum brake mechanism or other vacuum or suction actuated devices, with the intake manifold of the engine. It will be understood that the air exhausted from the suction actuated mechanism and delivered into the intake manifold necessarily tends to reduce the degree of rarefaction therein, and therefore to prevent the drawing in of the proper quantity of liquid fuel from the atomizer of the carburetor, or to dilute the explosive mixture passing through the suction passage frequently to

such an extent that the resulting mixture reaching the engine cylinders will not readily ignite. In either case, the engine, if turning over idly, would be likely to stall and the admission of air into the manifold in this manner may also materially delay the starting of the engine. It is also to be understood that for the proper operation of a vacuum brake mechanism of a motor vehicle, it is desirable that the air shall be withdrawn from the brake actuating mechanism as rapidly as possible in order to insure quick operation of the brake mechanism, and that the use of any restriction in the passage connecting the brake actuating mechanism with the intake manifold, for the purpose of avoiding the stalling of the engine and delay the starting, would necessarily result in retarding the operation of the brake mechanism to a greater or less extent, and is therefore undesirable.

It is also to be understood that in the operation of vacuum brake mechanisms, the moving part of the suction actuated device is acted upon by differential pressures brought about by producing a condition of rarefaction on one side of the piston, under the control of suitable reversing valve mechanism, and that the air so admitted is withdrawn and delivered into the suction passage of the engine, usually the intake manifold, that is to say, between the throttle and the cylinder ports.

The object of our invention is to provide means in connection with a multi-cylinder internal combustion engine for preventing the air withdrawn from a suction actuated device operatively connected with a suction passage of the engine, and delivered thereto, from stalling the engine or materially interfering with the operation thereof, and it consists in providing the engine with a plurality of independent carburetors, each of which is connected with a suitable manifold for supplying charges of explosive mixture to certain cylinders only of the engine and connect the suction from the vacuum

actuated device, as a power actuator for operating the brake mechanism of the vehicle propelled by the engine to one only of said manifolds, so that when the suction actuated device is operated in such manner as to effect the withdrawal of considerable quantities of air therefrom, said air will be delivered into a suction passage, or manifold, supplying only a portion of the cylinders of the engine, and while it may somewhat interfere with the operation of the cylinders connected with such suction passage, or manifold, it will have no effect whatever on the operation of the other cylinders of the engine, which are supplied by a different suction passage and a different carburetor, so that the engine will not in any case be stalled, but will continue to operate under the action of the explosions in the cylinder connected with the suction passage, or passages, to which the suction pipe from the actuator is not connected. For example, in the case of a four cylinder engine, we may employ two carburetors, each connected with a manifold supplying explosive charges to two cylinders only, and connect the suction pipe to one of said manifolds. As an example of the manner in which our invention may be embodied, in the case of a six cylinder engine, we may employ two carburetors connected to separate manifolds, each supplying explosive charges to three cylinders, or we may employ three carburetors and three separate manifolds, each supplying explosive charges to two cylinders, and in either case connect the suction pipe from the suction actuated device, to one manifold only. In like manner, the invention may be embodied in engines having eight, twelve, sixteen or more cylinders, in which separate carburetors and separate manifolds supply different groups of cylinders.

In the accompanying drawings,

Fig. 1 is a diagrammatic view showing an installation in an automotive vehicle, comprising an internal combustion engine of the multi-cylinder type, brake mechanism for the vehicle, and a vacuum or suction operated power actuator for the brake mechanism, and having our present invention embodied therein.

Fig. 2 is an enlarged sectional view of one form of power actuator which may be conveniently employed in an installation of this kind.

Fig. 3 is an enlarged elevation of the engine showing the separate manifolds and separate carburetors for supplying groups of the cylinders with explosive charges.

In Fig. 1, we have illustrated our invention applied in connection with an automotive vehicle propelled by a multi-cylinder internal combustion engine, and having a vacuum or suction actuated device for operating the brake mechanism of the vehicle. It is to be

understood, however, that the suction actuated device may be employed for other purposes in connection with the vehicle, and that the installation may be employed in any type of vehicle, as a boat, aeroplane, etc. In this figure, 1 represents the cylinder of a power actuator of the kind illustrated in our former application for Letters Patent of the United States filed January 5, 1925, and given Serial No. 506, although we do not limit the use of our present invention to any particular type of suction actuator. The cylinder is in this instance provided with a double acting piston, 3, as shown in Fig. 2, and a hollow piston rod, 5, which is connected by a link, 73, to a brake lever, 72, for operating a brake mechanism of any usual or preferred construction, diagrammatically illustrated in Fig. 1, and comprising in this instance a brake band, 71 and brake drum, 70, so that the movement of the piston in one direction applies the brake, and in the opposite direction, releases the brake. The hub of the actuator piston is provided with reversing valve mechanism, which is operated by a longitudinally movable valve actuating rod, or sleeve, 20, extending therethrough and through the hollow piston rod, and projecting through the opposite end of the cylinder from the piston rod, said valve mechanism being so constructed as to place one end of the cylinder in communication with the suction line or pipe, 26, extending to a suction passage of the engine, and the other end of the cylinder in communication with the atmosphere and vice versa, according as the valve actuating sleeve is moved in one direction or in the other. The valve actuating sleeve is provided with an internal plug or partition, 23, the rear portion of the sleeve (to the right in Fig. 2), being connected to the atmosphere through an aperture, 5^a, in the hollow piston rod, and the opposite end of the valve sleeve being connected to a suction pipe, 26, at least a portion of which is flexible to permit of the movement of the valve sleeve, 20. In this instance we have shown the valve sleeve, 20, provided with two pairs of oppositely arranged valves, 40-41 and 42-43, loosely mounted on the valve sleeve, and having interposed between the valves of each pair, retracting and sealing members, 50, tending to seat the valves of each pair, said valves being opened by means of collars, 51, secured to the sleeve, 20, on opposite sides of the respective pairs of valves. The hub of the piston is provided with a centrally located suction chamber, 3^a, communicating with the suction portion of the sleeve, 20, and provided with an air inlet chamber 3^b, communicating with the atmosphere through lateral apertures in the other portion of the sleeve, 20. The piston is also provided with ports, 34 and 35, on opposite sides of the piston communicating

with the suction chamber, and with ports, 33 and 36, on opposite sides of the piston communicating with the air inlet chamber, 3^b, by suitable passages. In the form of actuator herein shown, the air is exhausted from the actuator cylinder, on both sides of the piston when the latter is in the normal or off position, so that the actuator cylinder itself serves also the purpose of a vacuum storage space, and obviates the necessity of providing an extraneous suction or vacuum tank. In this instance this is accomplished by providing the valve actuating sleeve, 20, with a stop, as for example, the shoulder, 21, in Fig. 2, which will arrest the sleeve in such position that when the piston is in its retracted position, the central valves, indicated at 41, and 42, of the reversing valve mechanism, will be held in open position and thereby place the cylinder on both sides of the piston in communication with the vacuum or suction pipe, 26, but the same results may be accomplished in other ways. The specific valve mechanism herein shown and described is covered by our former applications for Letters Patent of the United States, Serial No. 506, filed January 5, 1925, and Serial No. 13,103, filed March 5, 1925, and this valve mechanism, per se, will not be specifically claimed herein. It does, however cooperate with and form a part of our present invention.

60 represents an internal combustion engine, in this instance provided with six cylinders and having a plurality of manifolds, each supplying a group of cylinders, and each manifold being provided with a separate carburetor. In this particular instance, we have shown the engine provided with three manifolds, 61, 62 and 63, each of which is connected with two cylinders of the engine. Each manifold is provided with a separate carburetor, of any usual or desired type, the separate carburetors being indicated at 64, 65 and 66. We have also shown a separate throttle valve interposed between each carburetor and its manifold, the throttle valve being illustrated at 67, 68 and 69, respectively, which may be separately controlled or connected for joint operation, as indicated in the drawings. The suction pipe, 26, is connected to the manifold, 63, only, as shown in Figs. 1 and 3, the suction pipe being preferably provided with a check valve, as indicated at 26^a, to prevent any of the explosive mixture from passing into the actuator, and also to maintain the highest possible degree of rarefaction in the actuator.

60 The sleeve, 20, is operatively connected with a foot lever, 74, or other operator operated device, provided with a retracting spring, 75.

65 When the engine is running under normal conditions, and the actuator is not being

operated, all the cylinders of the engine will receive their full charges of explosive mixture without diminution or dilution. In the operation of the actuator, which admits air therefrom into a suction passage of the engine, it will affect only the manifold, 63, and the cylinders supplied thereby, and will have no effect whatever on the remaining cylinders of the engine, which will continue to function in the ordinary manner, and insure the continuous operation of the engine, even though air is admitted from the actuator into the manifold, 63, in sufficiently large quantities to prevent the ignition and explosion therein by either diluting the explosive mixture supplied to the manifold, 63, or so reducing the rarefaction therein as to prevent the proper amount of liquid fuel being thrown in thereto during a few revolutions of the engine shaft.

In practice we prefer to employ the actuator of the kind shown in Fig. 2, and previously described, for the reason that as a partial vacuum is maintained in the cylinder on both sides of the piston, when the latter is in the off or normal position, the operation of the foot lever in a direction to apply the brakes, will shift the sleeve, 20, and the reversing valve mechanism controlled thereby in such manner as to place the cylinder on the forward side of the piston (to the left in Fig. 2) in communication with the suction pipe, 26, and to place the cylinder in rear of the piston (to the right in Fig. 2) in communication with the air inlet chamber, 3^b, so that the brakes will be instantly applied, while no appreciable amount of air will be admitted into the intake manifold, 63. There will, therefore, be no appreciable effect on any part of the engine cylinders when the brakes are applied. When the reversing valve mechanism is moved in the opposite direction so as to place the rear portion of the cylinder in communication with the suction pipe, 26, and the forward portion of the cylinder in communication with the atmosphere, the air previously admitted to apply the brakes, will be withdrawn and delivered into the intake manifold, 63, and may be withdrawn in such quantities as to interfere with the operation of the cylinders supplied by the manifold, 63, but will not in any degree affect the cylinders supplied by the other manifold, or manifolds, so that even if the cylinder connected with the manifold, 63, should miss firing for one or more revolutions of the engine shaft, the engine cannot stall, and its operation will not be injuriously interfered with.

It is to be understood that our present invention can be carried into effect in connection with any suction actuated device of any ordinary or preferred construction. It will also be seen that there is an added ad-

vantage of employing in connection therewith, our improved actuator, in which the piston is submerged in a partial vacuum when in the off position, as this contributes 5 to produce more efficient results by reason of the fact that, as no appreciable quantity of air is admitted to the manifold, 63, when the brakes are applied, any retardation of the action of the actuator piston which 10 might be caused by the fact that it depends for its suction only on the pumping action of a group of the cylinders, and not upon the pumping action of all the cylinders, will effect only the return movement of the piston, which releases the brake. This does 15 not interfere with the highest efficiency of the braking system, as the application of the brakes will be instantaneous, as previously described.

20 What we claim and desire to secure by Letters Patent is:—

1. The combination with a multi-cylinder internal combustion engine provided with a plurality of suction passages, each of said 25 passages supplying explosive charges to certain only of the cylinders, a carburetor communicating with each of said suction passages, and a throttle valve in each of said passages, of a suction actuated device, an 30 air connection therefrom extending to certain of said suction passages less than the whole number thereof, whereby the withdrawal of air from said suction actuated device in the operation thereof will not affect 35 the operation of the engine cylinders receiving their explosive charges from the suction passage, or passages, not connected with the actuator.

2. The combination with a multi-cylinder 40 internal combustion engine, provided with a plurality of intake manifolds each supplying explosive charges to a separate cylinder, or cylinders of the engine, a separate carburetor for each of said manifolds, a throttle valve interposed between each carburetor and its manifold, of a suction actuated device and air connection extending from the suction actuated device to certain of said manifolds, less than the whole number thereof, 45 and connected thereto between the throttle valve, or valves, thereof and the engine cylinders, whereby the withdrawal of air from the suction actuated device will not affect the operation of the engine cylinders 50 connected with the manifold, or manifolds, not connected with the suction actuated device.

3. The combination with a multi-cylinder 60 internal combustion engine, provided with a plurality of intake manifolds, each connected with certain cylinders only of the engine, a separate carburetor for each manifold, and a throttle valve interposed between each carburetor and each manifold, 65 of a suction actuated device, an air connec-

tion therefrom to one manifold only between the throttle valve and the cylinders supplied thereby, whereby the withdrawal of air from the suction actuated device in the operation thereof will not affect the operation 70 of the engine cylinders connected to the other of said manifolds.

4. The combination with a multi-cylinder internal combustion engine provided with a plurality of independent suction passages, 75 each suction passage being connected with certain only of the engine cylinders, a separate carburetor for each of said suction passages, a throttle valve for each of said suction passages, a power actuator including 80 a cylinder, a double acting piston therein, and reversing valve mechanism, an air connection from said reversing valve mechanism to certain of said suction passages less than the whole number thereof, said valve 85 mechanism being constructed to connect the cylinder on both sides of the piston with said air connection when the actuator piston is in the off position, and means for supplying higher pressure fluid to the actuator 90 cylinder under the control of the reversing valve mechanism, and operator operated means for said reversing valve mechanism, whereby the withdrawal of air from the actuator cylinder in the operation thereof 95 will not affect the operation of the cylinders receiving their explosive charges from the suction passage not connected with said actuator, and whereby the actuator piston may be operated in one direction without admitting appreciable quantities of air to the suction 100 passages connected therewith.

5. In an automotive vehicle, the combination with a multi-cylinder internal combustion engine for propelling the same, said engine being provided with a plurality of suction passages, each of which supplies explosive charges to certain only of the engine cylinders, a separate carburetor connected with each of said suction passages, a throttle valve in each of said suction 105 passages, between the carburetor and the cylinders supplied therefrom, of a power actuator including a cylinder, a double acting piston therein, and reversing valve mechanism, an air connection from said reversing valve mechanism to certain of said suction 110 passages of the engine less than the whole number thereof, and means for supplying atmospheric air to the actuator cylinder under the control of said reversing valve mechanism, said reversing valve mechanism being constructed to connect the actuator cylinder on both sides of the piston with said air connection when the actuator piston is in off position, brake mechanism for the vehicle connected with the actuator piston, and an operator operated part for controlling the reversing valve mechanism, whereby the operation of the actuator 115 120 125 130 piston

ton in a direction to apply the brakes, will not admit appreciable quantities of air into the suction passage, or passages, connected with the actuator and the withdrawal of air from the actuator in the operation thereof will not affect the operation of the engine cylinders receiving their explosive

charges from the suction passage or passages not connected with the actuator.

In testimony whereof we affix our signatures.

CALEB S. BRAGG.
VICTOR W. KLIERSRATH.
